ELECTRON DISCHARGE TUBE CIRCUIT

Maximiliaan Julius Otto Strutt and Aldert van der Ziel, Eindhoven, Netherlands; vested in the Alien Property Custodian

Application March 29, 1941, Serial No. 385,792
In the Netherlands May 30, 1940

7 Claims. (Cl. 179—171)

This invention relates to a circuit-arrangement for amplifying, generating and/or frequency-transformation of electrical oscillations, which comprises a secondary electron-emission tube. In the present case a secondary-emission tube is to be understood to mean a discharge tube whose electrode-system includes a cathode, a control-grid, an anode and in addition at least one electrode which is coated with a material having the property of readily emitting secondary electrons when it is struck by a stream of primary electrons.

For a proper understanding of the invention, reference will be had to the accompanying drawing in which Fig. 1 shows a circuit known in the art and upon which the present invention is an improvement, Fig. 2 is a known circuit, the principle of which is utilized in the invention, and Figs. 3 and 4 are circuits of two embodiments according to the present invention.

It is known that in a circuit-arrangement comprising a secondary-emission tube regenerative back-coupling can be obtained in a simple manner by connecting the secondary-emission electrode to the control-grid and to the cathode through suitable impedances. A diagram embodying this known circuit-arrangement is represented in Fig. 1 which shows a secondary-emission tube 1 comprising a cathode 2, a control-grid 3, a screen-grid 4, a secondary-emission electrode 5 and an anode 6. Between the control-grid 3 and the cathode 2 is provided an input impedance 7 which may be constituted, for instance, by an oscillatory circuit tuned to the frequency of the oscillations to be amplified. Between the anode 6 and the cathode 2 is provided an output impedance 8, the screen-grid 4 is connected in the usual way to the cathode through a condenser 9 having a high capacity. For the sake of simplicity the direct current connections have been omitted in the drawing, but it will be appreciated that the control-grid 3 must be negatively biased, whereas the electrodes 4, 5 and 6 must be positively biased, the positive bias of the anode 6 being larger than that of the secondary-emission electrode 5.

To obtain regenerative back-coupling an impedance Z_1 is provided between the secondary-emission electrode and the cathode, while an impedance Z_2 is connected between the secondary-emission electrode and the control-grid. These impedances are so chosen that the input impedance 7 is supplied with a current which is in phase with the alternating control-grid voltage. In this case the fact is utilized that the

alternating current of the secondary-emission electrode is in phase with the alternating control-grid voltage; consequently the impedances Z_1 and Z_2 are so chosen that a part of this current flows to a control-grid without phase-displacement. In an amplifying circuit with regenerative back-coupling for undamping the circuit 7 or, at ultra-high frequencies, for removing the input-damping of tube 1, the impedance Z_1 may, for instance, be an ohmic resistance, and the impedance Z_2 may be a coupling condenser whose impedance is small relatively to that of the circuit 7. In a mixing arrangement, in which the regenerative back-coupling serves for generating the local oscillations the impedance Z_1 may, for instance, be constituted by an oscillatory circuit tuned to the frequency of the local oscillations, whereas the impedance Z_2 is constituted by a reactance whose sign corresponds to that of the reactance constituted by the input-circuit 7 of the local oscillations. In this case the circuit 7 is tuned to the frequency of the incoming oscillations, whereas the circuit 8 is tuned to the intermediate-frequency.

Again it is known to remove the input-capacity of a discharge tube by means of a back-coupling. The circuit-arrangement shown in Fig. 1 may be used with advantage also for this purpose. In this case the impedances Z_1 and Z_2 are so chosen that the current flowing to the control-grid leads in phase by 90° with respect to the alternating control-grid voltage, i. e. a part of the alternating current of the secondary-emission electrode is supplied to the control-grid with a lead of 90° . The two said measures may be combined by giving the current, which flows through the impedance Z_2 to the control-grid, such a value and phase that both undamping and removal of the input-capacity is obtained. In this way the input-impedance of the tube can be completely compensated at ultra-high frequencies.

It is to be noted that in the transmission of oscillations having a very high frequency, with which the transit time of the electrons is at least of the same order as the period of the oscillation to be transmitted, the fact must be taken into account that the alternating current of the secondary-emission electrode is displaced in phase relatively to the alternating control-grid voltage. When, for instance, this phase displacement amounts to about 90° a part of the current of the secondary-emission electrode must be transmitted without phase-displacement to the control-grid for removal of the input-capacity, whereas a phase-displacement of 90° must be

produced for removing the input-damping. For disposing of the input-capacity the impedances Z_1 and Z_2 , for instance, might then be both capacities or both ohmic resistances, and for disposing of the input-damping Z_1 might be an ohmic resistance and Z_2 a small capacity.

Furthermore it is known that in secondary-emission tubes it is advantageous to utilise the fact that the anode-current substantially corresponds and is oppositely directed to the current of the secondary-emission electrode, by connecting the output-impedance between the anode and the secondary-emission electrode, and by connecting the electric center of these impedances to the cathode. In this way an output voltage can be obtained which is symmetrical with respect to earth as a result of which transition of a single stage to a push-pull stage can be obtained in a simple manner. A known circuit arrangement of this kind is represented in Fig. 2 in which the direct-current connections have been omitted again. In this case the output impedance 8 is connected between the anode 6 and the secondary-emission electrode 5 , the electric center 10 of circuit 8 being connected to the cathode. Through the circuit 8 is set up a symmetrical voltage relatively to earth, which voltage may be supplied to the input circuit of a push-pull stage.

The circuit-arrangement shown in Fig. 2 has the drawback that back-coupling of the secondary-emission electrode to the control-grid for undamping the input-circuit and/or for removing the input-capacity, such as is used in the circuit shown in Fig. 1, is not possible because the provision of the required impedances Z_1 and Z_2 would entirely break the symmetry of the circuit.

According to the invention this drawback is obviated by making use of a tube comprising at least two succeeding secondary-emission electrodes of which the last one is connected to the anode through an output impedance whose electric center is connected to the cathode, back-coupling current being taken from a preceding secondary-emission electrode, which current is supplied to the control-grid in such a phase as to obtain undamping of the input circuit and/or a decrease in input-capacity. The back-coupling current is preferably taken from the first secondary-emission electrode as a result of which the advantage is obtained that the circuit may be very simple, since the current of the first secondary-emission electrode will be substantially in phase with the alternating control-grid voltage.

The invention will be more fully explained by reference to Figures 3 and 4 of the accompanying drawing representing, by way of example, two embodiments thereof.

Fig. 3 shows a circuit including a tube which comprises two succeeding secondary-emission electrodes 5 and 11 . The first secondary-emission electrode 5 , whose current is in phase with the alternating control-grid voltage at least at not too high frequencies, is connected across an impedance Z_1 to the cathode and across an impedance Z_2 to the control grid, said impedances being so chosen as to obtain undamping of the input-circuit and/or a decrease in input-capacity of the tube. The secondary-emission electrode 11 which directly precedes the anode and whose current at least approximately corresponds and is oppositely directed to the anode-current is connected to the anode through the output-imped-

ance 8 , whereas the center 10 of the output-impedance is earthed.

Fig. 4 represents a circuit according to the invention, wherein the input-circuit is also connected in push-pull arrangement. The input-impedance 1 is connected in push-pull arrangement to the control-grids 3 and $3'$ of two similar secondary-emission tubes 1 and $1'$, the center 12 of the input-impedance 1 being connected to earth. Each of the tubes 1 and $1'$ comprises two succeeding secondary-emission electrodes $5, 11$ and $5', 11'$ respectively. Of each tube the first secondary-emission electrode 5 and $5'$ respectively is connected to the cathode and to the control-grid through suitable impedances Z_1, Z_2 and Z_1', Z_2' respectively. The centrally earthed output-impedance 11 is connected between the two anodes 6 and $6'$, the last secondary-emission electrode 11 of the tube 1 being connected to the anode $6'$ of tube $1'$ through a condenser 13 , and the last secondary-emission electrode $11'$ of tube $1'$ being connected to the anode 6 of tube 1 through a condenser 14 .

What we claim is:

1. A circuit-arrangement comprising a secondary electron-emission tube, in which the tube used comprises a cathode, a control grid, at least two secondary-emission electrodes and an anode arranged in the order named, an input circuit connected between cathode and control grid, an output-impedance whose electric center is connected to the cathode connected between the anode and one of the secondary-emission electrodes, a first impedance connected from the other secondary-emission electrode to the control grid, and a second impedance connected from said electrode to the cathode, said impedances being of such value that a back-coupling current is derived from said other secondary-emission electrode and supplied to the control-grid in such a phase as to obtain undamping of the input-circuit and/or a decrease in the input-capacity of the tube.

2. A circuit for the amplification of high frequencies comprising an electron discharge tube provided with at least a cathode, a control grid, an anode, and a pair of secondary electron emitting electrodes interposed in the space between the control grid and anode, an output impedance connected between the anode and one of the secondary electron emitting electrodes, an input impedance connected between the control grid and cathode, and a composite impedance having one portion connected between the other of said secondary electron emitting electrodes and the control grid and another portion between said other emitting electrode and the cathode, the portions of said composite impedance being of such value and the current supplied to the control grid through said composite impedance being of such phase that the effective input impedance of the circuit and the input capacity of the tube are reduced.

3. A circuit for the amplification of high frequencies comprising an electron discharge tube provided with at least a cathode, a control grid, an anode, and a pair of secondary electron emitting electrodes interposed in the space between the control grid and anode, an output resonant circuit connected between the anode and one of the secondary electron emitting electrodes, an input resonant circuit connected between the control grid and cathode, a first impedance connected between the other of said secondary electron emitting electrodes and the control grid,

and a second impedance connected between said other emitting electrode and the cathode, said impedances being chosen of such sign and value as to reduce the damping of the input circuit and/or to decrease the input capacity of the tube. 5

4. A circuit for the amplification of high frequencies comprising an electron discharge tube provided with at least a cathode, a control grid, an anode, and a pair of secondary electron emitting electrodes interposed in the space between the control grid and anode, an output circuit connected between the anode and one of the secondary electron emitting electrodes, a tunable input circuit connected between the control grid and cathode, a capacitive reactance connected 15 between the other of said secondary electron emitting electrodes and the control grid, and a resistance connected between said other emitting electrode and the cathode, said reactance and resistance being of such value that the damping of the input circuit is substantially reduced. 20

5. A circuit for the amplification of high frequencies comprising an electron discharge tube provided with at least a cathode, a control grid,

an anode, and a pair of secondary electron emitting electrodes interposed in the space between the control grid and anode, an output circuit having its electrical center connected to the cathode connected between the anode and one of the secondary electron emitting electrodes, an input circuit connected between the control grid and cathode, a first impedance connected between the other of said secondary electron emitting electrodes and the control grid, and a second impedance between said electrode and the cathode, said impedances being chosen of such sign and value that the input capacity of the tube is substantially reduced.

6. A circuit in accordance with the invention defined in claim 5, wherein the first and second impedances are each constituted by a resistance.

7. A circuit in accordance with the invention defined in claim 5, wherein the first impedance is constituted by a capacity and the second impedance is constituted by a resistance.
